153,537

DESIGN FOR A WAFFLE OR THE LIKE

Nicolas Milano, Euclid, Ohio

Application April 12, 1948, Serial No. 145,650

Term of patent 14 years

(Cl. D8—1)

To all whom it may concern:

Be it known that I, Nicolas Milano, a citizen of the United States, residing at Euclid, in the county of Cuyahoga and State of Ohio, have invented a new, original, and ornamental Design for Waffle or the like, of which the following is a specification, reference being had to the accompanying drawing, forming part thereof.

I claim:

The ornamental design for a waffle or the like, as shown.

NICOLAS MILANO.
